UNITED STATES PATENT OFFICE.

ALFRED A. KINNE, OF MINNEAPOLIS, MINNESOTA.

DESIGN FOR AN OIL-STOVE.

SPECIFICATION forming part of Design No. 23,709, dated October 16, 1894.

Application filed August 21, 1894. Serial No. 520,932. Term of patent 7 years.

To all whom it may concern:

Be it known that I, ALFRED A. KINNE, of the city of Minneapolis, county of Hennepin, State of Minnesota, have invented and produced 5 a new and original Design for Oil Heaters or Stoves, of which the following is a specification, reference being had to the accompanying drawing, showing the same and consisting in a single perspective view, which is 10 deemed all that is necessary to fully illustrate the design.

The features of my design consist in the low annular base ring 2, distinguished by the annular arrangement of scallops 3 which are 15 perforated. Above this rises a low cylindrical base extension, distinguished by an annular fluted or corrugated surface 4 and topped by a smooth surfaced reduction base 5. Above this rises the upper smaller cylindrical portion of the stove, of a greater height in itself than the height of the base, and distinguished by two of the annular fluted or corrugated surfaces 6 and 7.

A further distinguishing feature of the up-

per part consists in the window and frame in 25 the forward portion thereof, while the plainness of the stove is removed by the use of the large ring 8, the forward portion of which is extended or enlarged, as shown.

The upper part of the casing is crowned by 30 a cornice ring 9 and an ornamental top 10, the curves of which are ogee curves and are relieved by scallops 11. A suitable urn 12 is arranged upon the top 10.

The general effect of the design is neat and 35 symmetrical, and gives the impression of lightness and nice finish.

Having thus described my invention, I claim as new and desire to secure by Letters Patent—

The design for oil heaters or stoves, substantially as herein shown and described.

In testimony whereof I have hereunto set my hand this 18th day of August, A. D. 1894.

ALFRED A. KINNE.
